UNITED STATES PATENT OFFICE

ARMAND CLAUDE MORAND, OF SAN FRANCISCO, CALIFORNIA

DESIGN FOR A CHILD'S PLAY SUIT

Application filed March 16, 1932. Serial No. 43,212. Term of patent 7 years.

To all whom it may concern:

Be it known that I, ARMAND C. MORAND, a citizen of the United States, residing at San Francisco, in the county of San Francisco and State of California, have invented a new, original, and ornamental Design for a Child's Play Suit, of which the following is a specification, reference being had to the accompanying drawings, forming a part thereof,

In the drawings, Fig. 1 is a front view of a child's play suit showing my new design; and

Fig. 2 a rear view thereof.

I claim:

The ornamental design for a child's play suit, as shown.

ARMAND CLAUDE MORAND,
